United States Patent Office

Des. 233,222
Patented Oct. 15, 1974

233,222

AUTOMOBILE

Jack R. Finegan, Toorak, Victoria, Australia, and John K. Wasenko, Wiesbaden, Germany, assignors to General Motors Corporation, Detroit, Mich.

Filed Nov. 9, 1973, Ser. No. 414,327

Term of patent 14 years

Int. Cl. D12—08

U.S. Cl. D12—91

Fig. 3

Fig. 4

FIG. 1 is a side elevational view of an automobile showing our new design;

FIG. 2 is a top plan view taken generally along the plane indicated by line 2—2 of FIG. 1;

FIG. 3 is a front elevational view taken generally along the plane indicated by line 3—3 of FIG. 1;

FIG. 4 is a rear elevational view taken generally along the plane indicated by line 4—4 of FIG. 1; and

FIG. 5 is a perspective view.

The broken lines shown in FIGS. 1, 3, 4 and 5 are for illustrative purposes only.

We claim:

The ornamental design for an automobile, substantially as shown and described.
